(57) **CLAIM**

The ornamental design for an insert for food bowl, as shown and described.

DESCRIPTION

FIG. 1 is a top perspective view of an insert for food bowl showing my new design.

FIG. 2 is a bottom perspective view of the insert for food bowl shown in FIG. 1.

FIG. 3 is a front view of the insert for food bowl shown in FIG. 1.

FIG. 4 is a back view of the insert for food bowl shown in FIG. 1.

FIG. 5 is a right side view of the insert for food bowl shown in FIG. 1.

FIG. 6 is a left side view of the insert for food bowl shown in FIG. 1.

FIG. 7 is a cross-sectional view of the insert for food bowl taken along line 7-7 shown in FIG. 8.

FIG. 8 is a top view of the insert for food bowl shown in FIG. 1.

FIG. 9 is a bottom view of the insert for food bowl shown in FIG. 1; and,

FIG. 10 is a perspective view of the insert for food bowl shown in an environment of use.

The broken lines illustrating additional inserts in FIG. 10 show environment and form no part of the claimed design.

1 Claim, 6 Drawing Sheets
